CLAIM

The ornamental design for a magnetic card reader and door knob assembly, as shown and described.

DESCRIPTION

FIG. 1 is a front elevational view of a magnetic card reader and door knob assembly showing the first embodiment of our new design;

FIG. 2 is a left side elevational view thereof, the right side being a mirror image of that shown;

FIG. 3 is a top plan view thereof;

FIG. 4 is a top, front, and left side perspective view thereof;

FIG. 5 is a front elevational view of a magnetic card reader and door knob assembly showing the second embodiment of our new design;

FIG. 6 is a left side elevational view thereof, the right side being a mirror image of that shown;

FIG. 7 is a top plan view thereof; and,

FIG. 8 is a top, front, and left side perspective view thereof.
